UNITED STATES PATENT OFFICE.

RALPH K. THOMSON, OF SIOUX FALLS, SOUTH DAKOTA.

DESIGN FOR AN AUTOMOBILE SIDE-CURTAIN.

56,109.

Specification for Design.

Patented Aug. 17, 1920.

Application filed November 29, 1919. Serial No. 341,546. Term of patent 14 years.

To all whom it may concern:

Be it known that I, RALPH K. THOMSON, a citizen of the United States, residing at Sioux Falls, in the county of Minnehaha and State of South Dakota, have invented a new, original, and ornamental Design for Automobile Side Curtains, of which the following is a specification, reference being had to the accompanying drawing, forming part thereof.

The figure is an elevation of an automobile side curtain, showing my new design.

I claim:

The ornamental design for an automobile side curtain, as shown.

RALPH K. THOMSON.
